UNITED STATES PATENT OFFICE.

ALBERT O. GALE AND ELDOR J. IVERSON, OF SEATTLE, WASHINGTON.

COUPLING.

1,041,712.

Specification of Letters Patent.

Patented Oct. 15, 1912.

Application filed November 30, 1910. Serial No. 594,922.

To all whom it may concern:

Be it known that we, ALBERT O. GALE and ELDOR J. IVERSON, both citizens of the United States, and residents of Seattle, in the county of King and State of Washington, have invented certain new and useful Improvements in Couplings, of which the following is a full, true, and exact specification.

10 The principal object of this invention is to provide simple, effective and quick acting means for coupling together the ends of hose, line shafting, or the like, and in the operation of which no wrenches or other 15 tools are necessary.

Referring to the accompanying drawing, Figure 1 is a side elevation of our device in locked position. Fig. 2, an end elevation of the same. Fig. 3 is a central longitudinal 20 sectional view of Fig. 1. Fig. 4, a side elevation of the righthand locking member. Fig. 5, a side elevation of the corresponding lefthand member. Fig. 6, a side elevation of the collar, partly in section. Fig. 7, a side 25 elevation of the cap, partly in section. Fig. 8, an end elevation of Fig. 7, looking toward the left. Fig. 9, a side elevation of the two principal locking members in locked engagement of each other, and stripped of the 30 other parts.

Referring now more particularly to the drawings, the numeral 1 designates a central core which, if the coupling be used for hose, may be hollow, as shown, and to 35 the lefthand end of which may be attached in any suitable manner, one of the sections of hose to be coupled. Around the outer surface of the core 1, and firmly secured thereto, are the oppositely disposed curved 40 plates 3, projecting from which are the studs 4. The righthand end of the core 1 is tapered as at 5.

6 designates a collar, having the annular knurled rib 7, annular groove 8, and cam 45 slots 9. From the internal surface of the collar 6, and extending toward the center thereof, are the oppositely disposed raised portions 10.

11 designates a cap which is bored to fit 50 the lefthand end of the collar 6, and in which are the screws 12, which fit and wipe around in the annular groove 8 of the collar 6. The end of the cap 11 is counter-bored as at 13, to fit the core 1. Extending from 55 the end of the cap 11 are the tongues 13A.

14 is the righthand locking member,

which may be bored as at 14A, and to the outer end of which may be suitably connected the hose to be coupled, and, for convenience in handling may have the annular 60 rib 15. Extending from the lefthand end of the locking member 14 are the oppositely disposed shell-like projections, 16, which are substantially counterparts of the plates 3, of the core 1. The plates 3 and the extensions 16 are of equal thickness and represent arcs of the same circle, the former 65 adapted to enter the spaces between the latter (Fig. 9).

If Fig. 3 be considered especially in connection with Fig. 9 it will be seen that the core 1 and the righthand locking member 14, when in the positions there shown, can have no rotary movement with relation to each other, the projections 16 of the right- 70 hand locking member 14, the tongue 13A of the cap 11 and the plates 3 of the core 1 being substantially in contact with each other, and encircling the core 1; neither can longitudinal movement occur, the same being 75 prevented by the engagement of the studs 4 with the slots 9 of the collar 6. If either the core 1 or the righthand locking member 14 be now held against rotation and the knurled rib 7 upon the collar 6 80 turned in the direction of the arrow, Fig. 2, until the studs 4 reach the offsets 17 in the slots 9, the core 1 and the member 14 may be drawn apart until arrested by the contact of the studs 4 with the righthand 85 edges of the slots 9, when the rotation of the collar 6 may be continued until again arrested by the contact of the studs 4 with the ends of the slots 9. During this entire 90 rotation the slight cam action of the slots 9 upon the studs 4 has forced the collar 6 and its cap 11 together with its tongue 13A toward the left, withdrawing the free ends 95 of the latter from between the plates 3 of the core 1 and the projections 16 of the member 14, so that the member 14 and the core 1 may be rotated with relation to each other sufficiently to bring the plates 3 and the projections 16 into such position as to entirely clear each other and allow the core 100 1 and the member 14 to be completely separated. If the operation just described be 105 now reversed it is obvious that the coupling may be returned to its locked position.

The raised portions 10 are concaved to fit 110 the cylindrical surface of the core 1, and are of equal thickness with the plates 3, but are

not of sufficient width to interfere with the movement of the core 1 just described; their function being merely to form a wider bearing for the inner surface of the cap 6 upon the cylindrical surface of the core 1 than would otherwise exist.

From the foregoing description it will be seen that we have provided a coupling easy of manipulation, sure in its action and 10 which may be applied to hose, line shafting, or other like elements with equal efficiency, and that no wrenches or other tools are necessary to couple or uncouple the same.

We are fully aware that many minor 15 changes in the details of construction and arrangement of the parts will readily suggest themselves to others skilled in the art, without departing from the spirit and scope of our invention, and we do not, therefore, 20 desire to be limited to the exact form of embodiment herein shown and described.

Having described our invention, what we claim as new, and desire to protect by Letters Patent of the United States, is,—

25 A coupling comprising a pair of cylinders, one of which cylinders is provided with a

conical end portion and with locking plates rigidly and symmetrically disposed thereon, said locking plates having each a radially projecting stud, and the other of which cylinders is provided with an end adapted to fit the cone shaped end portion of said first named cylinder to make a fluid tight joint therewith and further provided with locking projections adapted to engage with said locking plates of said first named cylinder, and a collar having cam-slots and disposed on said first named cylinder which cam-slots are adapted to coöperate with said studs to forcibly engage said locking projections with said locking plates to rigidly unite said cylinders, in combination with an annular cap associated with said collar and with said first named cylinder, said cap having longitudinally extending tongues 45 adapted to prevent rotary movement of one of said cylinders with respect to the other.

ALBERT O. GALE.
